UNITED STATES PATENT OFFICE.

WILLIAM S. McLEWEE, OF NEW YORK, ASSIGNOR TO JACOB J. NICHOLS,
OF BROOKLYN, N. Y.

DESIGN FOR A HANGING LAMP.

SPECIFICATION forming part of Design No. 13,334, dated October 10, 1882.

Application filed July 12, 1882. Term of patent 7 years.

To all whom it may concern:

Be it known that I, WILLIAM S. McLEWEE, of New York, in the county and State of New York, have originated a new Design for a Hanging Lamp, of which the following is a specification.

The design consists in a lamp-reservoir of an upwardly-tapering form and having a finial on the bottom.

10 The design also consists in a lamp-reservoir and a support therefor consisting of arms extending from the neck or upper portion.

The design also consists in a lamp-reservoir and a support therefor consisting of arms extending from the neck or upper portion and embellished with representations of flowers, leaves, and like devices.

15 The design also consists in a lamp-reservoir and a support therefor consisting of arms extending from the neck or upper portion and embellished with scroll-shaped figures.

The design also consists in a lamp-reservoir and a support therefor consisting of arms extending from the neck or upper portion and comprising triangular portions, hereinafter described.

20 The design also involves a novel configuration of hanger for the lamp.

The accompanying drawing represents a hanging lamp embodying my design.

25 A designates the lamp-reservoir. It may be made of glass or other suitable material, and tapers upwardly. At the bottom it has an ornamental finial, B. At the neck or upper portion it is surrounded by a band, C, from which extend arms D D. These arms are embellished

with scrolls a and representations of flowers, leaves, and like devices, b. At their outer ends are triangular portions c, to which are secured chains E. These chains pass around 30 pulleys on a hanger, G, and extend thence to a counter-balance, H. This hanger is made in the form of a bar having ornate finials, and surmounted at the center by a Gothic arch.

What I claim as my design, and desire to 35 secure by Letters Patent, is—

1. In a lamp, a reservoir of upwardly-tapering form, having a finial at the bottom, substantially as specified.

2. In a lamp, a reservoir and a support for 40 the reservoir consisting of the arms extending from the neck or upper portion, substantially as specified.

3. In a lamp, a reservoir and a support therefor consisting of arms extending from the neck 45 or upper portion and embellished with representations of flowers, leaves, and like devices, substantially as specified.

4. In a lamp, a reservoir and a support therefor consisting of arms extending from the neck 50 or upper portion and embellished with scroll-shaped figures, substantially as specified.

5. In a lamp, a reservoir and a support therefor consisting of arms extending from the neck 55 or upper portion and comprising triangular portions, substantially as specified.

6. The design for the hanger of the lamp, substantially as specified.

W. S. McLEWEE.
